ARRANGEMENT FOR CONTROLLING SPECIAL INDICATIONS OF DISTANT SIGNALS

Phillip F. Holden, Norfolk, Va., assignor to Westinghouse Air Brake Company, a corporation of Pennsylvania

Application June 3, 1947, Serial No. 752,076

7 Claims. (Cl. 246—219)

1

My invention relates to a railway signal control system, and particularly to a railway signal control system for signals for governing traffic movements in both directions over a stretch of railway track.

For governing traffic movements in opposite directions over a switch which connects a main track with an auxiliary track, manually controllable signals are commonly provided, which may for example, be of the color light type, and are arranged to normally display a stop indication. The signal which governs traffic movements in the facing direction over the switch may be provided with an upper arm or group of color lights for governing traffic movements along the main track over the switch in its normal position, and with a lower arm or group of color lights for governing traffic movements from the main track to the auxiliary track over the switch in its reverse position. For governing traffic movements approaching this signal, a distant signal may be provided having an upper arm or group of color lights and also a lower arm or group of color lights for providing special indications in addition to the usual clear and approach indications.

One feature of my invention is the provision of an arrangement for controlling the special indications of the distant signal by a line circuit including a control line conductor for the opposing home signal, and an approach line control conductor.

I shall describe one form of apparatus embodying my invention, and shall then point out the novel features thereof in claims.

The accompanying drawings, Figs. 1a and 1b, when placed end to end, with Fig. 1a on the left, constitute a diagrammatic view showing one form of apparatus embodying my invention, in which color light signals are employed, and in which a transfer relay is controlled to become energized if a train approaches the distant signal while one of the yellow lamps or the green lamp of the home signal is controlled to be lighted, and in which the transfer relay, upon becoming energized, completes a line circuit for energizing a polarized signal relay for controlling the special indications of the distant signal.

Similar reference characters refer to similar parts in the drawings.

Referring to the drawings, a stretch of single track railway, designated by the reference character X, is shown, over which traffic movements may be made in either direction. Track X is connected with an auxiliary track Z by a switch W which is shown in its normal position for traffic movements along track X. Switch W is operable, by any suitable means, to a reverse position for traffic movements from each of these tracks to the other. In order to simplify the drawing, each track, comprising two parallel series of track rails, is represented by a single line.

2

The stretch of main track X is divided by insulated joints 4 into sections o—a, a—b, b—c and c—e. Each of these sections is provided with a track circuit including a track relay, designated by the reference character TR with a distinguishing numerical prefix, connected across the rails adjacent one end of the section, and a suitable source of current, such as a battery 2, connected across the rails adjacent the opposite end of the section.

A home signal 6S having an upper group u of green, yellow and red lamps, designated by the reference characters G, Y and R, respectively, and a lower group d of yellow and red lamps Y and R, respectively, is shown at point b. Signal 6S governs traffic movements toward the left, as shown in the drawing, which I shall assume is the westbound direction, off of section b—c and over section a—b in which switch W is located. Lamp G or lamp Y of group u, upon being lighted in conjunction with lamp R of group d, directs traffic movements over switch W in its normal position along track X, and lamp Y of group d, upon being lighted in conjunction with lamp R of group u, directs traffic movements over switch W in its reverse position from track X to track Z.

A distant signal 8S, comprising an upper group u of green, yellow and red lamps G, Y and R, respectively, and a lower group d of green, yellow and red lamps G, Y and R, respectively, governs westbound traffic movements into section b—c toward home signal 6S.

Traffic movements in the eastbound direction are governed by signals 4S, 5S and 7S, each of which comprises a single group of green, yellow and red lamps G, Y and R, respectively.

Signal 7S is controlled by a signal relay 7HD, only a portion of the control circuit for which is shown including a contact of relay 7TR. A direction stick relay 7SR, associated with signal 7S, is controlled in a well-known manner to become energized when an eastbound train enters section 7TR while relay 7HD is energized for controlling lamp G or lamp Y of signal 7S to be lighted. Signal 5S is controlled in part by a relay 5HD.

The upper group u of lamps of signal 6S is controlled by a home relay u6H and by a distant relay 6D. Relay 6D is controlled in a well-known manner by traffic conditions so that it is energized if track X is unoccupied for a given distance west of signal 5S. Relay 6D is therefore shown controlled by a circuit which includes a contact 50 of track relay 5TR similarly to the circuit for relay 7HD which includes contact 35 of track relay 7TR. The lower group d of the lamps of signal 6S is controlled by a home relay d6H. Relays u6H and d6H are controlled by a manually operable lever 6V which has a normal position n and a reverse position r, and by a contact 26 which is operated in conjunction with switch W so as to be closed in a normal position.

when switch W occupies its normal position and to be closed in a reverse position when switch W occupies its reverse position.

Light-out relays, designated by the reference characters 6GLO and u6YLO, are energized in series with lamps G and Y, respectively, of upper group *u* of the lamps of signal 6S, so that if either of these lamps becomes burned out, the light-out relay which is in series with it will become deenergized. A third light-out relay d6LO is energized in series with lamp Y of lower group *d* of the lamps of signal 6S. A light-out relay u8LO is also energized in series with lamp Y of upper group *u* of the lamps of signal 8S.

An approach locking relay, designated by the reference character 5ALS, is shown controlled in a suitable well-known manner which is common for approach locking relays, by a back contact of home relay 5HR, so that it will be energized only if signal 5S is so controlled that its red lamp is to be lighted.

The lamps of the upper group *u* of signal 8S are controlled by a slow release polarized signal relay u8HD. The lamps of lower group *d* of signal 8S are controlled by a slow release polarized signal relay d8HD.

An approach relay, designated by the reference character 6A, is normally energized, but becomes deenergized when a westbound train approaches signal 8S, and remains deenergized while section *b*—*c* is occupied by a train.

A transfer relay 6F is normally deenergized, but becomes energized when relay 6A becomes deenergized, if relay u6H or d6H is energized.

Having described, in general, the arrangement of the various parts of apparatus embodying my invention, I shall now describe the circuits and operation in detail.

As shown by the drawings, all parts of the apparatus are in the normal condition, that is, switch W is in its normal position; signals 4S, 5S and 6S are indicating stop; lamp G of signal 7S is lighted; upper lamp Y and lower lamp R of signal 8S are lighted; the track sections are unoccupied, and therefore the track relays are energized; each of the levers 5V and 6V is in its normal position *n*; relay 5HD is energized by current of normal polarity; relay u8HD is energized by current of reverse polarity; relays 5ALS, 6D, 6A, 7HD and u8LO are energized; and relays u6H, d6H, 5HR, 6GLO, u6YLO, d6LO, 6F, 7SR and d8HD are deenergized.

Relay 7HD is normally energized by a circuit which includes contact 35 of relay 7TR.

The circuit by which relay 5HD is energized by current of normal polarity passes from terminal 1B of a suitable source of current, shown as a battery 1Q, through the back point of contact 3 of relay 7SR, front point of contact 4 of relay 7HD, contact 5 of relay 8TR, back point of contact 6 of relay 6F, winding of relay 5HD, contact 7 of relay 8TR, and the back point of contact 8 of relay 7SR to terminal 1N of the same source of current. Signal 5S is also controlled in part by manual means, which may, for example, be a relay 5HR controlled by a manually operable lever 5V similarly to the manner in which relay u6H is controlled by lever 6V for controlling the upper group *u* of the lamps of signal 6S. Although relay 5HD is normally energized by the circuit just traced, signal 5S is normally controlled by relay 5HR to indicate stop, so that red lamp R of signal 5S is normally lighted by a circuit passing from terminal EB of a suitable source of lighting current, shown as a battery

EQ, through the back point of contact 39 of relay 5HR, and lamp R to terminal EN of the same source of lighting current.

Lamp R of upper group *u* of the lamps of signal 6S is lighted by a circuit passing from terminal EB, through the back point of contact 9 of relay u6H, and lamp R to terminal EN. Lower lamp R of signal 6S is lighted by a similar circuit, which includes the back point of contact 11 of relay d6H.

Relay 5ALS is normally energized by circuit means including a back contact 40 of relay 5HR.

Relay u8HD is energized by current of reverse polarity in a circuit passing from terminal B, through the back point of contact 12 of relay 6GLO, contact 7 of relay 8TR, winding of relay u8HD, contact 13 of relay 7SR, contact 14 of relay 8TR, contact 15 of relay 6TR, contact 16 of relay 5ALS, and the back point of contact 17 of relay 6GLO to terminal N. Relay u8LO is energized, and upper lamp Y of signal 8S is lighted, by a circuit passing from terminal EB, through the front point of contact 18 of relay u8HD, contact 19 of relay u8HD in its reverse position, winding of relay u8LO, and upper lamp Y to terminal EN. Lower lamp R of signal 8S is energized by a circuit passing from terminal EB, through the back point of contact 20 of relay d8HD, and lower lamp R to terminal EN.

Lamp G of signal 7S is energized by a circuit passing from terminal EB, through the front point of contact 48 of relay 7HD, contact 49 of relay 7HD in the normal position, and lamp G of signal 7S, to terminal EN.

Approach relay 6A is energized by a circuit passing from terminal 1B, through the back point of contact 3 of relay 7SR, front point of contact 22 of relay 7TR, contact 23 of relay 8TR, back point of contact 24 of relay 6F, winding of relay 6A, contact 7 of relay 8TR, and the back point of contact 8 of relay 7SR to terminal 1N.

I shall assume that, with apparatus as shown in the drawing, a leverman arranges for a westbound traffic movement over switch W in its normal position by moving lever 6V to its *r* position. I shall assume further that traffic conditions west of signal 6S are such that relay 6D is deenergized.

With lever 6V in its *r* position and switch W in its normal position, relay u6H will be energized by a circuit passing from terminal B, through contact 25 of lever 6V closed in the *r* position, contact 26 of switch W in its normal position, and the winding of relay u6H to terminal N. With relay u6H energized and with relay 6D deenergized, relay u6YLO will be energized and upper lamp Y of signal 6S will be lighted by a circuit passing from terminal EB, through the front point of contact 9 of relay u6H, back point of contact 10 of relay 6D, winding of relay u6YLO, and upper lamp Y to terminal EN. Lower lamp R of signal 6S remains lighted by its circuit previously traced.

With relay 6GLO still deenergized, relay u8HD is still energized by current of reverse polarity in its circuit previously traced. Relay u8LO and upper lamp Y of signal 8S are therefore energized by their circuits previously traced, and lower lamp R of signal 8S is also lighted by its circuit previously traced. I shall also assume further that a westbound train now approaches, and deenergizes relays 7TR and 7HD.

With relay 7TR deenergized, the circuit previously traced for relay 6A will be open at the front point of contact 22 of relay 7TR, causing relay 6A to be deenergized. With relay 6A de-

energized and relay $u6H$ energized, a circuit is completed for energizing relay $6F$, this circuit passing from terminal B, through contact 27 of relay $u6H$, contact 29 of relay $6A$, and the winding of relay $6F$ to terminal N.

With relay $7HD$ deenergized, the circuit previously traced for relay $5HD$ will be open at the front point of contact 4 of relay $7HD$, causing relay $5HD$ to be deenergized.

With relays $u6YLO$ and $6F$ energized, and with relays $7HD$ and $7TR$ deenergized, relay $d8HD$ will now be energized by current of reverse polarity in a circuit passing from terminal B, through contact 30 of relay $u6YLO$, back point of contact 31 of relay $d6LO$, front point of contact 24 of relay $6F$, contact 23 of relay $8TR$, back point of contact 22 of relay $7TR$, contact 32 of relay $u8LO$, winding of relay $d8HD$, back point of contact 4 of relay $7HD$, contact 5 of relay $8TR$, front point of contact 6 of relay $6F$, back point of contact 33 of relay $d6LO$, and contact 34 of relay $u6YLO$ to terminal N. With relay $d8HD$ energized by current of reverse polarity, lower lamp Y of signal $8S$ will now be lighted by its circuit passing from terminal EB, through the front point of contact 20 of relay $d8HD$, contact 21 of relay $d8HD$ closed in the reverse position, and lower lamp Y of signal $8S$ to terminal EN. With both lamps Y of signal $8S$ now lighted, this signal displays one of the special indications referred to, which is known as an advance approach indication.

If, while the westbound train is approaching signal $8S$, traffic conditions west of signal $6S$ should change, so that relay $6D$ becomes energized and opens its contact 10 at the back point, relay $u6YLO$ and upper lamp Y of signal $6S$ will be deenergized. With contact 10 of relay $6D$ then closed at its front point, relay $6GLO$ and lamp G of signal $6S$ will be energized by a circuit passing from terminal EB, through the front point of contact 9 of relay $u6H$, front point of contact 10 of relay $6D$, winding of relay $6GLO$, and lamp G of signal $6S$ to terminal EN.

With relay $u6YLO$ deenergized, its contacts 30 and 34 will open the circuit previously traced for relay $d8HD$, causing relay $d8HD$ to be deenergized. With relay $d8HD$ deenergized, lower lamp Y of signal $8S$ will be extinguished and lower lamp R of this signal will again be lighted.

With relay $6GLO$ now energized, relay $u8HD$ will be energized by current of normal polarity in a circuit which is the same as the circuit previously traced for energizing this relay by current of reverse polarity except that it includes the front points of contacts 12 and 17 of relay $6GLO$ instead of the back points of these contacts. With relay $u8HD$ energized by current of normal polarity, upper lamp G of signal $8S$ will be lighted by a circuit passing from terminal EB, through the front point of contact 18 of relay $u8HD$, contact 19 of relay $u8HD$ closed in the normal position, and upper lamp G of signal $8S$ to terminal EN. With contact 19 of relay $u8HD$ now closed in the normal position, relay $u8LO$ and upper lamp Y of signal $8S$ will be deenergized. With upper lamp G and lower lamp R of signal $8S$ now lighted, this signal will display the clear indication.

I shall now assume that the westbound train moves over the stretch of track shown in the drawing, and that all parts of the apparatus are returned to the normal condition as shown in the drawing. I shall assume further that switch W is then moved to its reverse position, and

that a leverman arranges for a westbound traffic movement over switch W in its reverse position by moving lever 6V to its r position.

With lever 6V in its r position and switch W in its reverse position, relay $d6H$ becomes energized by a circuit passing from terminal B, through contact 25 of lever 6V, contact 26 of switch W in its reverse position, and the winding of relay $d6H$ to terminal N. With relay $d6H$ energized, relay $d6LO$ becomes energized, and the lower lamp Y of signal $6S$ becomes lighted, by a circuit passing from terminal EB, through the front point of contact 11 of relay $d6H$, winding of relay $d6LO$, and lower lamp Y to terminal EN. Signal $6S$, therefore, now displays the restricting indication shown by lighting upper lamp R over lower lamp Y.

Relay $u8HD$ is now energized by its reverse energizing circuit previously traced. Relay $u8LO$ is therefore now energized, and upper lamp Y of signal $8S$ is lighted by the circuit previously traced.

I shall assume that a westbound train now approaches signal $8S$, deenergizing relays $7TR$ and $7HD$ as before. Relay $6A$ will therefore become deenergized as previously described. With relay $d8H$ now energized, relay $6F$ becomes energized by a second circuit, passing from terminal B, through contact 28 of relay $d6H$, contact 29 of relay $6A$, and the winding of relay $6F$ to terminal N.

With relay $d6LO$ now energized, relay $d8HD$ becomes energized by current of normal polarity in a circuit which is the same as the circuit previously traced for this relay except that it includes the front points of contacts 31 and 33 of relay $d6LO$ instead of the back points of these contacts and contacts 30 and 34 of relay $u6YLO$. With relay $d8HD$ energized by current of normal polarity, the lower lamp G of signal $8S$ becomes lighted by its circuit passing from terminal EB, through the front point of contact 20 of relay $d8HD$, contact 21 of relay $d8HD$ closed in the normal position, and lower lamp G of signal $8S$ to terminal N. With upper lamp Y and lower lamp G of signal $8S$ now lighted, this signal displays another special indication, known as the approach medium indication.

I shall next assume that a leverman arranges for an eastbound traffic movement by placing lever 5V in its r position. Relay $5HR$ then becomes energized by its circuit passing from terminal B, through contact 43 of lever 5V, and the winding of relay $5HR$ to terminal N.

Relay $5HR$, upon becoming energized, opens its back contact 49, thereby causing relay $5ALS$ to be deenergized. Contact 16 of relay $5ALS$ thereupon opens the reverse energizing circuit previously traced for relay $u8HD$, causing relay $u8HD$ to be deenergized. With relay $u8HD$ deenergized, its contact 18 opens at its front point, thereby extinguishing upper lamp Y of signal $8S$. A circuit for lighting upper lamp R of signal $8S$ is then closed through the back point of contact 18 of relay $u8HD$.

Relay $5HR$, upon becoming energized, also opens its contact 39 at the back point, thereby extinguishing lamp R of signal $5S$. Contact 39 of relay $5HR$, upon becoming closed at its front point, completes a circuit for lighting lamp G of signal $5S$, this circuit passing from terminal EB, through the front point of contact 39, front point of contact 44 of relay $5HD$, contact 45 of

relay 5HD closed in the normal position, and lamp G of signal 5S to terminal EN.

When the leverman returns lever 5V to its *n* position, relay 5HR becomes deenergized. Lamp G of signal 5S is thereby extinguished, and lamp R of signal 5S is again lighted. Also, contact 40 of relay 5HR becomes closed in circuit means for again energizing relay 5ALS.

When the eastbound train enters section *b-c*, relay 5HD becomes deenergized by the opening 10 of contacts 5 and 7 of relay 8TR.

When the eastbound train enters section *c-e*, relay 7TR becomes deenergized, and relay 7HD is then deenergized by the opening of contact 35 of relay 7TR. Contact 48 of relay 7HD then opens at its front point, thereby extinguishing lamp G of signal 7S. Lamp R of signal 7S then becomes lighted by its circuit which includes the back point of contact 48 of relay 7HD.

Relay 7HD is slow releasing, and therefore its 20 contact 37 remains closed at its front point for a brief period of time after relay 7HD becomes deenergized. During this brief period of time, relay 7SR is energized by a pickup circuit passing from terminal B, through contact 36 of relay 25 7TR, front point of contact 37 of relay 7HD, and the winding of relay 7SR, to terminal N. A stick circuit for relay 7SR then becomes closed, passing from terminal B, through contact 36 of relay 30 7TR, contact 38 of relay 7SR, and the winding of relay 7SR, to terminal N.

When the eastbound train leaves section *b-c*, relay 5HD becomes energized by current of reverse polarity passing from terminal 1B, through the front point of contact 3 of relay 7SR, contact 1 of relay 8TR, winding of relay 5HD, back point of contact 6 of relay 6F, contact 5 of relay 8TR, and the front point of contact 8 of relay 7SR, to terminal 1N. If lever 5V is then moved to its *r* position, so that relay 5HR is energized, lamp Y of signal 5S will be lighted by a circuit passing from terminal EB, through the front point of contact 39 of relay 5HR, front point of contact 44 of relay 5HD, contact 45 of relay 5HD in its reverse position, and lamp Y of signal 5S, to terminal EN.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a railway signal control system for signals for governing traffic movements in both directions over a stretch of railway track, including a home signal adjacent one end of said stretch for governing traffic movements in a given direction off of said stretch and including a distant signal adjacent the opposite end of said stretch for governing traffic movements in said stretch for governing traffic movements in said given direction over said stretch toward said home signal and also including a third signal adjacent said home signal for governing traffic movements in the opposite direction over said stretch, the combination comprising, a traffic responsive relay which is normally energized but which becomes deenergized if a train approaches said distant signal in said given direction, a polarized signal relay for controlling said distant signal, an approach relay for said home signal, a transfer relay, a circuit controlled by a front contact of said traffic responsive relay for energizing said approach relay, means for at times controlling said home signal to display a given indication and for at other times controlling said home signal to display a second indication, circuit means controlled by a back contact of said approach relay for energizing said transfer relay, a circuit controlled by a front contact of said transfer relay for energizing said polarized signal relay by current of normal or reverse polarity according as said home signal is controlled to display said given indication or said second indication respectively, a circuit controlled by a back contact of said approach relay for energizing said transfer relay if said home signal is controlled to display either said given indication of said second indication, and means including a back contact of said transfer relay for controlling said third signal.

and by a back contact of said transfer relay for energizing said approach relay, means for at times controlling said home signal to display a given indication and for at other times controlling said home signal to display a second indication, circuit means controlled by a back contact of said approach relay for energizing said transfer relay if said home signal is controlled to display either said given indication of said second indication, and means including a back contact of said transfer relay for controlling said third signal.

2. In a railway signal control system for signals for governing traffic movements in both directions over a stretch of railway track, including a home signal adjacent one end of said stretch for governing traffic movements in a given direction off of said stretch and including a distant signal adjacent the opposite end of said stretch for governing traffic movements in said given direction over said stretch toward said home signal and also including a third signal adjacent said home signal for governing traffic movements in the opposite direction over said stretch and including a fourth signal adjacent said distant signal for also governing traffic movements in said opposite direction, the combination comprising, a track relay and a signal control relay for said fourth signal both of which are normally energized but which become deenergized if a train approaches said fourth signal in said given direction, a polarized signal relay for controlling said distant signal, an approach relay for said home signal, a transfer relay, a circuit controlled by a front contact of said track relay and by a back contact of said transfer relay for energizing said approach relay, means for at times controlling said home signal to display a given indication and for at other times controlling said home signal to display a second indication, circuit means controlled by back contacts of said track relay and said signal control relay and by said transfer relay in its energized condition for energizing said polarized signal relay by current of normal or reverse polarity according as said home signal is controlled to display said first or said second indication respectively, a circuit controlled by a back contact of said approach relay for energizing said transfer relay if said home signal is controlled to display either said first or said second indication, and means including a back contact of said transfer relay for controlling said third signal.

3. In a railway signal control system for signals for governing traffic movements in both directions over a stretch of railway tracks, including a home signal adjacent one end of said stretch for governing traffic movements in a given direction off of said stretch and including a distant signal adjacent the opposite end of said stretch for governing traffic movements in said given direction over said stretch toward said home signal and also including a third signal adjacent said home signal for governing traffic movements in the opposite direction over said stretch and including a fourth signal adjacent said distant signal for also governing traffic movements in said opposite direction, the

combination comprising, a traffic responsive relay for controlling said fourth signal and which is normally energized but which becomes deenergized if a train approaches said fourth signal in said given direction, a stick relay which becomes energized if a train passes said fourth signal in said opposite direction and which then remains energized while said traffic responsive relay is deenergized, a signal relay for controlling said distant signal, an approach relay, a transfer relay, a circuit controlled by said stick relay and by said transfer relay both in the deenergized condition and by said traffic responsive relay in its energized condition for energizing said approach relay, means for at times controlling said home signal to display a given indication, a circuit controlled by a back contact of said approach relay for energizing said transfer relay if said home signal is controlled to display said given indication, and a circuit controlled by said traffic responsive relay in the deenergized condition and by said transfer relay in the energized condition for energizing said signal relay if said home signal is displaying said given indication.

4. In a railway signal control system for signals for governing traffic movements over a given stretch of railway track, including a home signal adjacent one end of said stretch for governing traffic movements in a given direction off of said stretch and including a distant signal adjacent the opposite end of said stretch for governing traffic movements in said given direction over said stretch toward said home signal, the combination comprising, a traffic responsive relay which is normally energized but which becomes deenergized if a train approaches said distant signal in said given direction, a signal relay for controlling said distant signal, an approach relay, a transfer relay, a circuit controlled by a front contact of said traffic responsive relay and by a back contact of said transfer relay for energizing said approach relay, means for at times controlling said home signal to display a given indication, a circuit controlled by a back contact of said approach relay for energizing said transfer relay if said home signal is controlled to display said given indication, and a circuit controlled by a back contact of said traffic responsive relay and by a front contact of said transfer relay for energizing said distant signal, a circuit controlled by a back contact of said approach relay and by control means for said home signal for energizing said transfer relay, and means including a back contact of said transfer relay for controlling said third signal.

5. In a railway signal control system for signals for governing traffic movements in both directions over a stretch of railway track, including a home signal adjacent one end of said stretch for governing traffic movements in a given direction off of said stretch and including a distant signal adjacent the opposite end of said stretch for governing traffic movements in said given direction over said stretch toward said home signal and also including a third signal adjacent said home signal for governing traffic movements in the opposite direction over said stretch, the combination comprising, a traffic responsive relay which is normally energized but which becomes deenergized if a train approaches said distant signal in said given direction, a signal relay for controlling said distant signal, an approach relay, a transfer relay, a circuit controlled by a front contact of said traffic responsive relay and by a back contact of said transfer relay for energizing said approach relay, means for at times

controlling said home signal to display a given indication, a circuit controlled by a back contact of said traffic responsive relay and by a front contact of said transfer relay for energizing said signal relay if said home signal is controlled to display said given indication, a circuit controlled by a back contact of said approach relay for energizing said transfer relay if said home signal is controlled to display said given indication, and means including a back contact of said transfer relay for controlling said third signal.

6. In a railway signal control system for signals for governing traffic movements in both directions over a stretch of railway track, including a home signal adjacent one end of said stretch for governing traffic movements in a given direction off of said stretch and including a distant signal adjacent the opposite end of said stretch for governing traffic movements in said given direction over said stretch toward said home signal and also including a third signal adjacent said home signal for governing traffic movements in the opposite direction over said stretch, the combination comprising, a traffic responsive relay which is normally energized but which becomes deenergized if a train approaches said distant signal in said given direction, an approach relay, a transfer relay, a circuit controlled by a front contact of said traffic responsive relay and by a back contact of said transfer relay and also by traffic conditions between said home and distant signals for controlling said approach relay, a circuit controlled by a back contact of said traffic responsive relay and by a front contact of said transfer relay for controlling said distant signal, a circuit controlled by a back contact of said approach relay and by control means for said home signal for energizing said transfer relay, and means including a back contact of said transfer relay for controlling said third signal.

7. In a railway signal control system for signals for governing traffic movements over a given stretch of railway track, including a home signal adjacent one end of said stretch for governing traffic movements in a given direction off of said stretch and including a distant signal adjacent the opposite end of said stretch for governing traffic movements in said given direction over said stretch toward said home signal, the combination comprising, a traffic responsive relay which is normally energized but which becomes deenergized if a train approaches said distant signal in said given direction, an approach relay, a transfer relay, a circuit controlled by a front contact of said traffic responsive relay and by a back contact of said transfer relay for energizing said approach relay, a circuit controlled by a back contact of said approach relay and by control means for said home signal for energizing said transfer relay, and means controlled by a back contact of said traffic responsive relay and by a front contact of said transfer relay for controlling said distant signal.
